UNITED STATES PATENT OFFICE.

CHRISTIAN JORGENSEN, OF LAKE FOREST, ILLINOIS.

WRENCH.

1,086,058.

Specification of Letters Patent.

Patented Feb. 3, 1914.

Application filed September 19, 1913. Serial No. 790,694.

To all whom it may concern:

Be it known that I, CHRISTIAN JORGENSEN, a citizen of the United States, residing at Lake Forest, in the county of Lake and State of Illinois, have invented certain new and useful Improvements in Wrenches, of which the following is a specification, reference being had to the accompanying drawings.

10 This invention relates to new and useful improvements in wrenches, and more particularly to a wrench which is most readily adaptable for use in connection with pipes, and the primary object of the invention is 15 to provide a device of this character which is quickly and readily adjustable to any size of object, and which will be most effective in use.

A further object of the invention resides 20 in providing a wrench with a movable jaw capable of adjustment when the same is disposed in one position with respect to the stationary jaw, and a still further object resides in providing a device which is automatically locked in its adjusted position 25 by the actuation of the wrench.

With these and other objects in view, my invention consists in the novel features of construction, combination and arrangement 30 of parts to be hereinafter referred to and more particularly pointed out in the specification and claim.

In the accompanying drawing forming a part of this application, Figure 1 is an elevation of the device in its normal position showing in dotted lines the position of the movable jaw and shank thereof when the device is applied to use. Fig. 2 is a vertical section through the device, also showing in 35 dotted lines the position of the movable jaw and shank thereon in their effective positions. Fig. 3 is a horizontal section therethrough as seen on line 3—3 of Fig. 1.

In describing the invention, I shall refer 40 to the drawing in which similar reference characters designate corresponding parts throughout the several views and in which 1 indicates a shank, the inner end of which forms a handle member, and the outer portion of which is enlarged and designed to 45 form a stationary jaw 2. The upper face of this jaw is arranged substantially in a horizontal plane when the device is held in proper position, and said face is provided 50 with inwardly inclined teeth 3.

A U-shaped keeper or swinging member

4 has the sides thereof embracing the side faces of the outer enlarged portion of the shank below the jaw 2 and pivoted thereto on a transverse pivot 5. This keeper or swinging member projects rearwardly of the shank and receives for sliding movement therein an additional bar or shank 6. The outer end of this bar or shank 6 is bent to form an acute angle with respect to the shank 5 or bar proper and is designed to form a movable jaw 7 for coöperation with the stationary jaw 2. The contacting face of the jaw 7 is also toothed, as shown at 8, for coöperation with the teeth 3 of the stationary 65 jaw.

The contacting of the jaws 3 and 7 obviously limits the inward movement of the shank or bar 6 in the keeper or swinging member 4, and a transverse pin or stud 9 is adapted to engage the under edge of said keeper or swinging member 4 to limit the outward movement of said shank. A leaf spring 10 secured at its inner end to the rear 70 edge of the shank 1 intermediate the ends thereof, is bent outwardly or rearwardly with respect to the shank 1 and has the outer end thereof contacting with the front edge of the additional shank or bar 6, forcing the latter outwardly into somewhat binding engagement with the base portion of the U-shaped swinging member 4. This spring, therefore, yieldingly retains the shank and movable jaw thereon somewhat in their adjusted positions.

The front edge of the shank or bar 6 is provided with outwardly inclined teeth 11, the purpose of which will presently appear. The enlarged upper portion of the shank 1 is slotted from its rear edge, as shown at 12, and the transverse pivot 5 passes through the walls of this slotted portion. Also pivotally carried on this pivot 5 and projecting beyond the rear face of the enlarged upper portion of the shank is a gravity dog 13 which has limited swinging movement and is adapted to engage the teeth 11 on the inner side edge of the bar 6. The teeth 11 will engage said dog 13 upon the disposition inwardly of the inner portion of said bar or shank 6 toward the shank 1 against the tension of the spring 10 and as it is obvious from the inclination of the movable jaw with respect to the stationary jaw that the disposition of a pipe or other object between said jaws will swing said shank or bar 6 to

a position for engagement with the gravity dog 10, it will be seen that the locking of the shank and movable jaw in their adjusted positions will be automatic through the 5 actuation of the device.

From the foregoing description of the construction of my improved device, the operation thereof will be readily understood. It will be seen that I have provided a wrench 10 which is simple and durable in construction, inexpensive to manufacture, and one which will be very efficient and useful in operation.

While I have particularly described the elements best adapted to perform the functions set forth, it is obvious that various changes in the form, proportion and in the minor details of construction may be resorted to, within the scope of the appended claim, without departing from the spirit 20 or sacrificing any of the principles of the invention.

Having thus described my invention, what I claim, is:

A wrench of the class described comprising 25 a shank having an enlarged outer portion thereon and provided with a stationary jaw at the outer end of said enlarged

portion, a U-shaped keeper having the sides thereof pivoted to the sides of the enlarged portion of the shank and projecting beyond 30 the rear edge of the latter, an additional shank slidably mounted in the projecting portion of said keeper, and having a movable jaw formed on the outer end thereof designed for coöperation with the stationary jaw, the front edge of said shank opposed to the rear edge of the first mentioned shank being also provided with upwardly inclined teeth, a gravity dog pivotally carried on the enlarged portion of the shank 35 and adapted for engagement with the teeth of the second mentioned shank when the latter is swung to certain positions with respect to the first mentioned shank, and a leaf spring carried on the first mentioned shank 40 and bent outwardly for engagement with the second mentioned shank at a point below the keeper.

In testimony whereof I hereunto affix my signature in the presence of two witnesses. 50

CHRISTIAN JORGENSEN.
